Homer & Brown

UNITED STATES PATENT OFFICE.

WILLIAM P. CUNNINGHAM, OF NORRISTOWN, PENNSYLVANIA.

APPARATUS FOR CASTING CHAIN-LINKS.

1,295,703.

Specification of Letters Patent.

Patented Feb. 25, 1919.

Application filed August 30, 1918. Serial No. 252,117.

To all whom it may concern:

Be it known that I, WILLIAM P. CUNNINGHAM, a citizen of the United States, and a resident of Norristown, county of Montgomery, State of Pennsylvania, have invented certain Improvements in Apparatus for Casting Chain-Links, of which the following is a specification.

My invention relates to certain improvements in apparatus set forth in my pending application Serial No. 244,034, filed July 9th, 1918.

One object of my invention is to provide means for hardening the bearing surfaces of the links made in accordance with my invention.

A further object of the invention is to provide a removable chill.

In the accompanying drawing:—

20 Figure 1, is a plan view of a flask showing the pattern of a quarter of two links with the chill in position;

Fig. 2, is a sectional view on the line 2—2, Fig. 1;

25 Fig. 3, is a perspective view of the chill;

Fig. 4, is a view looking at one end of the chill;

Fig. 5, is a view looking at the opposite end of the chill;

30 Fig. 6, is an inverted plan view of the chill;

Fig. 7, illustrates sufficient of a mold showing the two chilled sections in position to chill the wearing surfaces of the links of the chain; and

Fig. 8, is a diagrammatic view indicating the chilled surfaces of coupled links.

1 is the bottom board and 2 is the flask of the ordinary construction. Secured to the 40 bottom board is a pattern 3, which is one-quarter of one of the links of the chain to be cast. 4 is one-quarter of one of the other links of the chain to be cast. This pattern, in the present instance, is made in two parts

45 5 and 6. The part 5 is the curved section forming one-half of the end of the link and this section has a projecting pin 7, which enters a hole in the bottom board 1 so as to retain it in place. The other section 6 has 50 a portion 8, which is one-quarter of the pattern of the connecting web which is present

in substantially all anchor chains. The sections 5 and 6 are perforated for the reception of a pin 9 which extends through the wall of the flask, as clearly shown in Fig. 2, and retains the pattern in place while the sand is being rammed around it. The patterns for the gates may be formed in any suitable manner.

55 In order to harden the surfaces *x* and *y* of the enchain links, which bear one upon another, I provide a chill 10 of steel or other suitable material. This chill is made as clearly shown in Figs. 3 to 6, inclusive, and has a groove 11 which fits the portion 5 and 65 a groove 12 which fits the portion 3. These two grooves are at right angles to each other, as shown, and flanges 13, which are on each side of the groove 11, extend on each side of the portion 5 so that the surfaces *x* and *y* of 70 the links, Fig. 8, are chilled when the metal forming the links is poured into the mold.

75 The process of casting the chain according to my improved process is as follows:—The pattern is set in the mold, as clearly shown in Figs. 1 and 2, with one-half of the chill in position. The sand is then placed in the flask and rammed around the pattern and then the pattern is assembled with like patterns to form a completed link and the chills 80 of two adjoining patterns are in contact, as illustrated in Fig. 7, making a complete chill member for the bearing surfaces of the two enchain links. The molten metal is poured in any suitable manner into the mold 85 cavities and that portion of the metal coming in contact with the chill will be hardened, as indicated in Fig. 8.

I claim:—

90 1. In an apparatus for casting chains, the combination of a quarter mold having a mold cavity therein for a portion of two chains; a metallic chill having curved grooves at right angles, one to the other, conforming to the shape of the links to be cast 95 so that when the casting is made the bearing faces of the links will be hardened.

95 2. In apparatus for casting chains, the combination of two quarter molds having mold cavities therein for portions of two chains; a metallic chill having curved grooves at right angles, one to the other, con-

forming to the shape of the links to be cast, so that when two of these molds are assembled a complete chill is formed for the bearing surfaces of the two enchain'd links.

5 3. In an apparatus for casting chains, the combination of a mold with a metallic chill having two curved grooves, one at an angle

to the other and forming, with the mold, cavities for the links to be cast, the chill hardening the bearing surfaces of each of 10 the cast links.

In witness whereof I affix my signature.

WILLIAM P. CUNNINGHAM.
